UNITED STATES PATENT OFFICE.

CLAUDE T. SPIVEY, OF FRESNO, CALIFORNIA, ASSIGNOR TO FRESNO AGRICULTURAL WORKS, OF FRESNO, CALIFORNIA.

SULPHURING MACHINE.

Application filed June 17, 1925. Serial No. 37,687.

My invention relates to a sulphuring machine, and more specifically to the device for feeding the sulphur into the blower pipe. It is well known that it is a common practice to dust certain vegetation with pulverized sulphur to prevent mildew, and on the larger ranches such dusting is done by power machinery. The pulverized sulphur is usually shipped in sacks, and owing to certain adhesive qualities, it sometimes forms into chunks so that it will not feed uniformly through a small aperture. To overcome this difficulty I have invented a mechanism which powders the sulphur within the hopper as it drops adjacent to the bottom of the hopper.

The object I have accomplished is the pulverizing of the sulphur preparatory to dusting it through a dusting device and a uniform feeding of the sulphur dust through the discharge opening in the hopper.

These objects are accomplished by means of the device hereinafter described and illustrated on the accompanying drawing, in which Figure 1 is a top view of the dusting machine with parts cut away showing the pulverizing device. Figure 2 is a fractional side view of the machine showing the hopper in section. Figure 3 is a top view of the rotary knife adapted to pulverize the sulphur. Figure 4 is a side view of the device shown in Figure 3.

In said drawing 5 is the frame of a sulphuring machine carried on traction wheel 6. The axle 7 to which the traction wheels are attached is adapted to rotate with the wheels, and carries a large drive wheel 19. An auxiliary shaft 9 carries a small gear 21, which is aligned with large gear 19 so that on the rotation of the gear 19 the motion is communicated to gear 21. Gear 21 rotates loosely on shaft 9, and by means of a clutch 23 gear 21 can be made to revolve shaft 9. Shaft 9 also carries rigidly attached thereto a gear 10^A, which rotates a gear 8 adapted to run loosely on shaft 7 by means of a belt 10. A gear 42 is attached to gear 8 and rotates with it, and by means of a belt or chain 45 communicates power to a fan 50. I have provided a tube 44 which receives the current of air from fan 50, and dispenses it through hose connections 46 and 47. Shaft 9 carries a

beveled gear 11 which actuates a similar gear 12. Gear 12 carries a shaft 13 which rotates an agitator A. Agitator A consists of a plurality of blades 30 which rotate on a common plane, and one or more arms 31, which extend above the plane covered by blades 30. I have provided a hopper 15 having a bottom 16, which is positioned on the frame of the vehicle so that the blades 30 will rotate directly above and on a plane with the bottom and within the hopper and the arms 31 will rotate on the plane of a cone. A hole 40 is made through the bottom of the hopper in a position whereby the blades 30 when rotating press directly over said hole and a lead from said hole enters the pipe 44.

It will thus be noted that when the vehicle is moved the traction wheels 6 will revolve the agitator A by means of the train of gears hereinbefore described, and also will make the fan 50 function to blow air through tube 44 and through hose connections 46 and 47. When the hopper has sulphur therein the agitator A tends to keep the opening 40 clear of lumps by cutting and pulverizing any lumps of sulphur which may be in the hopper, and which are adjacent to said opening, and the arms 31 tend to draw the sulphur down toward the knives and toward the bottom of the hopper if gravity should fail to properly function for that purpose and to break up the larger lumps.

For the purpose of limiting the size of hole 40, I have arranged a lid 41 which can be moved to cover hole 40 in whole or in part by moving the foot lever 43 up or down, said lever being connected with the lid by a rod 42.

Having described my invention, I claim as new and ask for Letters Patent:

In a dusting machine in combination with a hopper having a bottom and a discharge opening through said bottom, of an agitator consisting of a plurality of blades extending radially from a common center member, said center member being pivotally mounted and positioned so that when rotated the blades will pass over and adjacent to the discharge opening, said agitator having arms extending outward and angling upward from said common center member.

CLAUDE T. SPIVEY.
